UNITED STATES PATENT OFFICE.

JOHNSTON TURNER, OF SHEFFIELD, ENGLAND.

MOLDER'S FLASK, PATTERN-FRAME, AND ODD SIDE.

1,354,590.

Specification of Letters Patent.

Patented Oct. 5, 1920.

Application filed December 8, 1919. Serial No. 343,380.

To all whom it may concern:

Be it known that I, JOHNSTON TURNER, subject of the King of Great Britain and Ireland, and resident of 28 Plumpers road, 5 Sheffield, in the county of Yorkshire, England, have invented a certain new and useful Improvement in Molders' Flasks, Pattern-Frames, and Odd Sides, of which the following is a specification.

10 This invention relates to an improved method of constructing molders' flasks, odd-sides, pattern frames and the like and has for its object the production of articles which are light in weight, not liable to twist 15 or warp after continued use, and which can be produced more expeditiously and at less cost than in accordance with the present methods.

A further object consists in the adaptability of the improved construction to jig plates.

According to the invention the molder's flask is constructed of two sheet metal cylinders concentric with one another and arranged a short distance apart so as to form an annular space between the cylinders. This space is filled with slag or other suitable material, and in order to enable the material to obtain a firm grip on the sides of 20 the flask, both cylinders and walls are provided with a series of perforations or recesses. The perforations are formed by stamping or in any other suitable manner so as to form or leave a projecting edge or 25 flange around the hole projecting into the annular space between the walls of the flask. Handles are provided on opposite sides of the flask to enable it to be lifted. These handles are formed of round metal bar, split 30 at one end for a portion of their length, the split ends being bent at right angles to the handle portion and embedded in the filling material. The walls are provided at opposite ends with guide pins and metal bushes 35 or sockets respectively to enable the flask to register with corresponding pins or bushes arranged in or on an adjoining flask or molding plate or board.

The ends of the flask having bushes or 40 sockets in its outer edge, may be provided with a recess or window above the end of the bush to enable the hole in the bush to be kept free of sand and facilitate the operation of placing the flask in position on a sec- 45 ond flask or molding plate or board.

The molding plate or board may be provided with clearance holes within which are placed guide pins adapted to be locked when adjusted and in order to insure accurate adjustment of the guide pins, pieces of thin 60 sheet metal may be fixed to the board marked with center lines.

The method of constructing the flasks may also be applied to the making of pattern frames or odd sides.

In order that my invention may be readily understood reference is made to the accompanying drawings showing several applications of the invention by way of example, in which:—

Figure 1 is a plan view of a molder's flask, which may be used as a drag or a cope.

Fig. 2 is a section on the line A—A of Fig. 1.

Figs. 3 and 4 are part section and front 75 view showing a recess or window above the inner end of the bush or socket.

Fig. 5 is a sectional view of part of a deep flask provided with an inwardly projecting annular rim or lip to receive two or more 80 locking bars.

Fig. 6 is a sectional view through the locking bars.

Fig. 7 is a plan, and

Fig. 8 a section on the line B—B of Fig. 7 85 showing an odd-side for molding a simple curved perforation plate.

Figs. 9 and 10 are longitudinal section and plan respectively showing the application of the invention to a pattern frame.

Fig. 11 is a sectional view showing part of a molding plate.

Fig. 12 shows the invention applied to a jig plate.

Referring to Figs. 1 to 4, *a* is the other 95 casing and *b* the inner lining, both formed of sheet metal and arranged concentric with one another so as to form an annular space *c* between each wall. The annular space *c* is filled with slag or any other suitable material. Each wall is provided with a series of recesses or perforations *e* punched, stamped, or otherwise formed from the outside of the outer casing and from the inside of the inner lining. The holes may be of any convenient size and are formed so as to leave inwardly projecting jagged edges or flanges *e*¹. When the annular space is filled with the material, the edges of the recesses are firmly embedded while the outer surfaces of 100 105 110

the two walls present a comparatively smooth surface, the material being forced up into the holes level with the outer and inner flat surfaces of each wall respectively. The 5 lower end of the inner lining is provided with an inwardly projecting flange or lip k for the purpose of lifting the sand as the cope is lifted off.

The flask is provided at both ends with a 10 series of metal bushes or sockets f those at the upper end having nuts f^1 at the bottom of the bush to receive screwed pins. The bushes or sockets are preferably of such a size as to leave sufficient space between the 15 sides of the walls to permit the bushes to be completely embedded in the material. It will of course be understood that the bushes and pins on each end of the flask are arranged equidistant around the ends of the 20 flask so as to register with corresponding bushes or pins in an adjoining flask or molding plate or board.

The flask is provided with handles h projecting from opposite sides of the flask which 25 fit tightly into holes formed in the outer casing. These handles are preferably formed of round metal bar of the desired length the inner ends being split longitudinally and bent round at 90 degrees at h^1 30 so as to obtain a firm hold in the material with which the walls are filled.

In the construction shown in Figs. 3 and 4, bushes or sockets f are provided with a recess or window i above the inner end of 35 the bush opening through the outer wall a so as to enable the hole in the bush to be kept free of sand and facilitate the guiding of the flask on to a second flask or molding plate or board.

40 Fig. 5 shows a deep flask. The inner walls b in this case are provided at each end with an inwardly projecting lip or flange k cut away at a series of equidistant points in its periphery to receive the loose bars or 45 arms l shown in Fig. 6. These bars or arms are formed of side members l^1 and a middle member l^2 slightly shorter in length than the members l^1 and of the same thickness as the lip or flange k , the arms or bars, preferably four in number, are arranged at right 50 angles to one another in the form of a cross, and are adapted to be inserted into the cut away portions of the lip k and rotated so that the lip is engaged on each side by the members l^1 of the arms.

In Figs. 7 and 8, a similar method of construction is shown applied by way of example to an odd-side for molding a curved perforated plate, although it will be readily understood that the invention may be used for forming any desired shape or form of odd-side. The frame comprises longitudinal side members m of wood or other suitable material and transverse members n 60 while the frame is further strengthened by

cross members n^1 arranged at the base of the frame. The mold shown in the drawing is built up of sheet zinc side members o having recesses or perforations o^1 having inwardly projecting edges or flanges o^2 firmly embedded in the material. The upper surface is provided with a series of metal bushes r embedded in the mold and corresponding to the holes in the perforated plate to be molded. The upper surface may also have 75 a perforated sheet zinc casing similar to o if necessary.

The pattern frame (Figs. 9 and 10) is built up of side members t and cross members t^1 of wood or other suitable material 80 the frame being further strengthened by bolts t^2 passing transversely through the frame at each end. The bottom t^3 of the frame is supported by members t^4 so that the depth of the frame may be regulated to 85 suit the depth of the pattern. The pattern frame is provided at each end with bushes s which may if necessary have nuts located at their inner ends as shown to the left of Fig. 9 at s^1 . The odd-side is formed as 90 follows:

Pins s^2 are placed in these bushes and bushes q to be embedded in the odd-side are placed over the projecting ends of said pins. The perforated zinc forming the top and 95 sides of the odd-side is now laid on the bottom of the frame and bushes or pieces of tubular metal r^1 placed over the prints r , formed on the bottom t^3 to correspond with the perforations in the pattern. The frame 100 for the odd-side is now positioned on the pattern frame and plaster of Paris poured in. When the material has set, the whole is turned over so that the odd-side forms the drag and the pattern frame the cope. 105 The bushes q the zinc lining o and the bushes or pieces of tubular metal r are now firmly embedded in the odd-side as shown in Figs. 7 and 8.

The prints r are now taken out of the pattern frame and the pattern for the perforated plate placed in the frame. Guide pins are placed in the bushes of the pattern frame and also in the bushes of the odd-side to receive the flasks. 110

The odd-side is provided with handles p at each end for lifting, and with bushes q embedded in the body of the material at or near each end for receiving pins for securing the flask in correct position. Four 115 bushes may if necessary be supplied on each side or near the ends of the frame.

In order to further secure the bushes in flasks, odd-sides, molding plates or boards and the like, they may be provided with one 120 or more annular grooves q^1 as shown in Fig. 8.

In Fig. 11, which shows the method of securing the bushes in a molding plate, the bushes u are made fast in the plate by run- 130

ning spelter into the annular space u^1 between the bush u and the side of the recess in the plate, the latter being provided with one or more grooves u^2 in order to obtain a better hold on the material. The guide pin v with the bush and nut for embedding in the flask is placed in position as shown.

Fig. 12 shows the arrangement applied to a jig plate. The frame is constructed in the same manner as the flasks, the bushes w being the full depth of the frame as shown. In this case the three holes are bored in a board slightly larger than the diameter of the guide pins and when the pins are adjusted they are screwed up tight. The frame forming the jig is positioned on the board and plaster of Paris is filled in at w^1 . The guide pins are made a snug fit in the bushes, so that it is preferable to remove the board from the pins by unscrewing the nuts, and removing the pins from the jig plate separately.

What I claim as my invention and desire to obtain by Letters Patent is:—

25 1. Molders' flasks, pattern frames or odd-sides comprising a frame or casing having hollow walls, filling material packed in the hollow walls of the casing and recesses or perforations formed in the walls of the casing 30 to engage and retain the filling material, and inwardly projecting edges to the perforations.

2. Molders' flasks comprising two concentric metal frames placed one within the other so as to leave a space between them, filling material packed in the space between the frames, means for keying the filling material in place and sockets located in the filling material on the upper and lower faces 40 of the flask to receive guide pins for locating the flasks one above the other.

3. Molders' flasks comprising two concentric metal frames placed one within the other so as to leave a space between them, filling material packed in the space between the frames, means for keying the filling material in place, bars inserted through the outer casing into the filling material to form handles and split ends to these bars 50 which ends are bent outwardly and embedded in the filling material.

4. Molders' flasks, comprising two concentric metal frames placed one within the other so as to leave a space between them, filling material packed in the space between the frames, means for keying the filling material in place, sockets located in the filling material on the upper and lower faces of the flask to receive guide pins for locating the flasks one above the other, bars inserted through the outer casing into the filling material to form handles and split ends to these bars which ends are bent outwardly and embedded in the filling material.

65 5. Molders' flasks comprising two concentric metal frames placed one within the other so as to leave a space between them, filling material packed in the space between the frames, means for keying the filling material in place, inwardly projecting flanges 70 on the inner frames, recesses in these flanges, and bars having forked ends to engage in these recesses so that they may be turned so as to be locked upon the flange.

6. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges 75 on the inner frame, recesses in these flanges, and bars having forked ends to engage in these recesses so that they may be turned so as to be locked upon the flange.

7. Molders' flasks comprising two concentric metal frames placed one within the other so as to leave a space between them, filling material packed in the space between the frames, means for keying the filling material in place, bars inserted through the outer casing into the filling material to form 80 handles and split ends to these bars which ends are bent outwardly and embedded in the filling material, inwardly projecting flanges on the inner frame, recesses in these flanges, and bars having forked ends to engage in these recesses so that they may be turned so as to be locked upon the flange.

8. Molders' flasks comprising two concentric metal frames placed one within the other so as to leave a space between them, filling material packed in the space between the frames, means for keying the filling material in place and sockets located in the filling material on the upper and lower faces of the flasks to receive guide pins for locating the flasks one above the other and recesses or windows in the side wall and the outer frame communicating with the sockets to allow any sand accumulated in the sockets to pass out through these windows.

9. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

10 10. Molders' flasks comprising two concentric metal frames placed one within the other so as to leave a space between them, filling material packed in the space between the frames, means for keying the filling material in place, inwardly projecting flanges 105 on the inner frame, recesses in these flanges, and bars having forked ends to engage in these recesses so that they may be turned so as to be locked upon the flange and recesses or windows in the side wall and the outer frame communicating with the sockets to allow any sand accumulated in the sockets to pass out through these windows.

110 11. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

115 12. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

120 13. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

125 14. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

130 15. Molders' flasks comprising two concentric metal frames placed one within the other so as to leave a space between them, filling material packed in the space between the frames, means for keying the filling material in place and sockets located in the filling material on the upper and lower faces of the flask to receive guide pins for locating the flasks one above the other, inwardly projecting flanges on the inner frame, recesses in these flanges, bars having forked ends to engage in these recesses so that they may be turned so as to be locked upon the flange and recesses or windows in the side wall and the outer frame communicating with the sockets to allow any sand accumulated in the sockets to pass out through these windows.

with the sockets to allow any sand accumulated in the sockets to pass out through these windows.

10. Molders' flasks comprising two concentric metal frames placed one within the other so as to leave a space between them, filling material packed in the space between the frames, means for keying the filling material in place, bars inserted through the 10 outer casing into the filling material to form handles, split ends to these bars which ends

are bent outwardly and embedded in the filling material, inwardly projecting flanges on the inner frame, recesses in these flanges, bars having forked ends to engage in these 15 recesses so that they may be turned so as to be locked upon the flange and recesses or windows in the side wall and the outer frame communicating with the sockets to allow any sand accumulated in the sockets to pass out 20 through these windows.

JOHNSTON TURNER.
